UNITED STATES PATENT OFFICE.

JOHN GILLIES, OF NEW YORK, N. Y.

SAWING-MACHINE.

SPECIFICATION forming part of Letters Patent No. 637,961, dated November 28, 1899.

Application filed May 2, 1899. Serial No. 715,316. (No model.)

To all whom it may concern:

Be it known that I, JOHN GILLIES, a citizen of the United States, residing at New York, (Flushing,) in the county of Queens and State 5 of New York, have invented certain new and useful Improvements in Sawing-Machines; and I do hereby declare the following to be a full, clear, and exact description of the invention, such as will enable others skilled in the 10 art to which it appertains to make and use the same.

My invention relates to sawing-machines, and particularly to machines intended for sawing stone; and my invention consists in 15 the novel combination, construction, and arrangement of the parts.

The purpose for which my sawing-machine is particularly intended is the cutting up of long blocks of stone into blocks of shorter 20 length.

The object of my invention is to make the machine simple, effective, easily adjusted and operated, and comparatively inexpensive. This object is attained in the sawing- 25 machine herein described, and illustrated in the drawings which accompany and form a part of this specification, in which the same reference-numerals indicate the same or corresponding parts, and in which—

30 Figure 1 is a side elevation of the machine. Fig. 2 is a transverse section thereof through the center of the saw-carriage, the section being taken at right angles to Fig. 1. Fig. 3 is a plan view of the machine. Fig. 4 is a detail transverse section of one of the columns 35 which support the saw-carriage guide-frame, showing the means employed for guiding and adjusting vertically said frame; and Fig. 5 is a detail section of the same, showing the form 40 of the teeth.

In the drawings, 1 1 are columns of channel-section; 2 2, diagonal braces therefor; 3 3, top pieces connecting the end braces of the columns, and 4 a rectangular frame guided 45 by the column 1 and arranged to be adjusted vertically, by means to be hereinafter described, and provided with guides upon its upper and lower sides for guiding the movement of the saw-carriage 5, which surrounds 50 and is mounted upon the frame 4 and bears against the upper and lower guides thereof. Said saw-carriage is provided with bearings

for a saw-shaft 6, having secured thereto a saw 7. Said saw is underhung, so as to be particularly adapted for working on objects 55 beneath the carriage.

8 8 are I-beams forming the base of the machine.

9 9 are suitable guides for a work-carriage 10. The guides shown are ordinary railway- 60 rails, and the carriage 10 is a truck similar in construction to the trucks ordinarily used for handling stone in a stone-yard. The rails 9 9 are laid transversely from the saw-carriage guide-frame 4, the framework of the 65 machine being so constructed that the work-carriage 10, with a block of stone thereon, may pass underneath the guide-frame 4. The truck 10 may therefore be moved on the rails 9 until the point at which a cut is to be made 70 is exactly opposite the saw 7. The cut may then be commenced.

11 designates a stone upon the truck 10 in which a cut is being made. Suitable braces 12 for holding the stone stationary on the 75 truck may be provided.

The saw-carriage guide-frame 4 carries a revoluble driving-shaft 13. The saw-carriage 5 carries a worm 14, mounted upon said shaft 13 and driven therefrom by means of a key 80 or spline working within a groove 15 in the shaft 13. The saw-shaft 6 is provided with a worm-wheel 16, intermeshing with the said worm. Revolution of the shaft 13 therefore drives the saw. The saw-carriage 5 is traversed upon the guide-frame 4 by a screw 17, mounted in bearings in the frame 4 and working in a screw-threaded sleeve 18 of the carriage 5. The screw 17 is driven from the shaft 13 by bevel-gears 19, 20, 21, and 22. 90

As above stated, the columns 1 are of channel-section. The guide-frame 4 is provided with extensions 23, carrying on their ends guide-shoes working in the channels of the columns, these channels thus forming guides. 95 The frame 4 is also steadied against lateral movement by guide-pieces 24, bolted to the sides of the columns 1. Vertical screw-shafts 25 25, having bearing in the columns 1 and passing through the extensions 23 of the 100 frame 4, are provided for raising and lowering the frame 4. One of these screw-shafts 25 is provided with an operating-wheel 26, and the other screw-shafts are connected to

that shaft which is provided with the wheel by means of suitable gearing and shafts, as shown.

The driving-shaft 13 is provided with a belt-wheel 27, by which it may be rotated. This belt-wheel should be driven from a counter-shaft at such distance from the machine and so located that the necessary amount of vertical movement of the saw-carriage may take 10 place without materially altering the belt-tension.

The operation of the machine is as follows: A stone to be cut having been placed upon the truck 10 and said truck having been 15 moved on the rails or guides 9 until the point on the stone at which the cut is to be made is exactly opposite the saw 7, (which saw is then upon the left-hand side of the machine,) the revolution of the shaft 13 is commenced, 20 thus causing the saw to revolve and causing the saw-carriage to move to the right. The depth of cut is adjusted by means of the hand-wheel 26. After a cut is made the carriage may be returned to the left-hand side of the 25 machine by reversing the direction of revolution of the shaft 13 by any suitable means. After a cut has been completed at one point and the saw withdrawn the stone-carriage may be moved onward and a cut made at another point in the stone.

I prefer to use a saw having teeth shaped as shown in Fig. 5—that is, having a V-shaped cutting edge.

My practice is not to cut the stone completely through with the saw, but to cut within about one-fourth of an inch of the lower surface of the stone. The cut may then be finished by breaking the stone by means of 35 wedges or in any other suitable manner. The 40 ridges then remaining on the stone may be

removed by dressing. In this way injury to the edges of the stone may be avoided.

Having thus completely described my invention, what I claim, and desire to secure by Letters Patent, is—

1. In a sawing-machine, the combination, 45 with guides for a work-carriage, and a frame spanning said guides and adapted to permit the passage of a work-carriage beneath the same, and having a horizontal guide member 50 provided with guides for a saw-carriage upon its upper and lower sides, of a saw-carriage surrounding and mounted upon said guide member, an underhung saw revolvably mounted upon said saw-carriage, and in close proximity to the saw-carriage guide member, and means for driving the saw and traversing the saw-carriage.

2. In a sawing-machine, the combination, 55 with guides for a work-carriage, and a frame spanning said guides and adapted to permit the passage of a work-carriage beneath the same, and having a horizontal guide member 60 for a saw-carriage, of a saw-carriage surrounding and mounted upon said guide member and guided upon both the upper and the lower sides thereof, an underhung saw-shaft carried by said carriage, a saw thereon, a driving-shaft having a worm mounted thereon and connected thereto by a feather, and arranged to be moved along said driving-shaft 65 by the saw-carriage, and a worm-wheel on the saw-shaft intermeshing with the worm.

In testimony whereof I hereunto affix my signature in the presence of two witnesses. 70

JOHN GILLIES.
